UNITED STATES PATENT OFFICE.

NICOLAY FRITZNER, OF BERLIN, PRUSSIA, GERMAN EMPIRE.

BOTTLE-STOPPER.

SPECIFICATION forming part of Letters Patent No. 223,283, dated January 6, 1880.

Application filed June 11, 1879.

To all whom it may concern:

Be it known that I, NICOLAY FRITZNER, of Berlin, in the Kingdom of Prussia and German Empire, have invented a new and useful

5 Improvement in Bottle-Stoppers, of which the following is a specification.

The invention relates to that class of stoppers which, composed of a common cork and of the mechanical device, are used on bottles 10 for perfumes, fragrant essences, eau de cologne, and similar fluids, and which are constructed in such manner as to permit the fluid to be discharged in small quantities—if desired, in drops.

15 The object of my invention is to better secure the mechanical device to the cork, to increase the certainty that the fluid shall commence to be delivered promptly through a very limited opening, and by reducing the 20 surface wetted by the fluid beyond the stopping-point to economize the consumption in delivering small quantities.

25 In the accompanying drawings, in which similar letters of reference indicate like parts, Figure 1 is an axial section of my improved stopper. Fig. 2 is an elevation. Fig. 3 is a cross-section of the screw-cap on the line A B of Fig. 1. Fig. 4 is an axial section of such stopper simplified in some respect.

30 Similar letters of reference indicate corresponding parts in all the figures.

The cork-tube *a*, fastened to the cork *k* of the bottle by expanding the inner end of the tube *a*, as indicated by *a'*, after it is freely inserted, is provided with the shield *c* and the screw-threaded part *d*. The axial hole *e* of the cork-tube *a* narrows toward the top of the screw part *d*. The cap *b*, fitting with its female screw to the screw *d*, is provided in its 35 center with a cone *n*, and perforated by a single small outlet-hole, *p*, which, commencing at the side of the cone *n*, passes through the body of the cap *b* in an oblique direction, and opens or terminates in the center of the top of the cap *b*.

40 When the cap *b* is screwed down the cone *n* is forced into the opening of the hole *e* against its upper sharp edge, shutting off any discharge of the contents of the bottle. A little 45 back turning of the cap *b* allows the fluid to be discharged in single drops, and giving to

the cap *b* two or three turns more will open the passage to its full extent, so that the fluid may flow out in a small stream in proportion to the openings *e* and *p*.

55

Knurled rims *o* *h* facilitate the manipulating of the cap *b*.

To avoid the possibility of losing the cap *b* by unscrewing it entirely from the piece *d*, the former is provided on its lower extremity with 60 an annular upset, *m*, playing in a ring, *g*, projecting from the shield *c*. The upper edge, *l*, of this ring *g* is turned over to the inside, so as to lock the upset *m* if the cap *b* is screwed loose for two or three turns, and prevents, by 65 this means, the cap *b* from being lost. This arrangement of the stopper is represented in Figs. 1, 2, 3, while Fig. 4 shows it in its simpler form.

I prefer to cast the parts *a* and *b* of the stopper, say, in tin, britannia, or other metal, or in any other suitable material, so that all the work required after their casting is the insertion and the fastening of the part *a* to the cork *k* by the expanding or turning outward 70 of the lower end of the tube *a*, as shown, and the spinning over of the edge *l* after the cap *b* is screwed on the screw part *d*.

The locking of the mechanical device to the cork by the turning outward of the inner end 75 of the tube contributes to the durability and mechanical perfection of the device.

The tapering form of the hole *e* gives an ample passage at the inner end of the tube, so that the fluid can readily enter and the air escape so soon as the bottle is inverted, requiring but a small orifice at the outer end, which is stopped by the cone *n*. Providing a single hole, *p*, reduces the surface which is to be wetted by the fluid, and reduces the quantity of 85 fluid which is required to pass the stopped point *n* before it will begin to escape at the outer opening. This latter quality is of special importance in the use of fluids which are volatile, so that all the material left on the 90 surfaces will evaporate and be lost before the next use of the device, and also in the use of fluids which, like some of the oils, oxidize and change by contact with the air.

95 Ordinary devices of this kind have two or 100 more holes. I have discovered that one will serve better.

I claim as my improvement in bottle-stoppers—

1. The screw-threaded tube *a*, having the tapering orifice *e*, in combination with the controlling-cone *n*, tapered in the opposite direction, screw-cap *b*, and cork *k*, as herein specified.
2. The screw-threaded tube *a*, having aperture *e*, tapered throughout, the locking-flange or expanded end *a'*, and the cap-shield *c*, in

combination with the threaded cap *b*, having controlling-cone *n* and single inclined passage *p*, and with the cork *k*, as and for the purposes set forth.

This specification signed by me this 22d day 15 of April, 1879.

NICOLAY FRITZNER.
